WEDGE ARRANGEMENT FOR A HOT TOP

BACKGROUND OF THE INVENTION

Hot top structures of the type contemplated herein are used to insulate the top of an ingot mold in order to delay the cooling of the molten metal in the hot top. In some instances, particularly in steel making, exothermic materials are incorporated in the panels which make up the hot top structure to provide heat around the top of the ingot to further delay cooling of the molten metal in the hot top at the top of the ingot. This molten metal will fill the cavity which forms in the ingot upon solidification of the molten metal.

The insulating panels or sideboards which make up the hot top structure are suspended in the top of the ingot mold in a closely spaced relation to the adjacent panels. The molten metal, as it rises in the ingot, flows into the space between the panels and the ingot mold. If a sufficient amount of molten metal enters the space between the panel and the ingot mold, the panel will float in the molten metal destroying the insulating effect of the panel.

Efforts to overcome this problem as seen in U.S. Pat. No. 3,421,731 have resulted in the elimination of the floating problem. However, the panels which are used to form the hot top structure in this patent have grooves provided in the panels for the wedges. These grooves have weakened the panels to such an extreme that a high rate of breakage of the panels has resulted.

SUMMARY OF THE INVENTION

The hot top structure disclosed herein provides an improved wedging arrangement for a hot top structure formed from a plurality of panels. This wedging arrangement reduces breakage in the panels, as well as preventing floating of the panels in the molten metal in the ingot mold. The wedging arrangement includes a clip which is mounted on the edges of each panel and a wedging member that is inserted between the clips and adjacent panels to wedge the panels against the ingot mold. The clip provides a bearing surface for the wedging member to thereby eliminate undue stresses in portions of the panel. Recesses are provided in the edges of each panel to positively locate the clips and prevent their movement during implacement of the panels in the hot top.

Other advantages of the invention will be apparent from the following description when read in connection with the accompanying drawing, in which:

FIG. 1 is a perspective view of the upper portion of an ingot mold showing the wedging attachment.

FIG. 2 is a view taken on line 2-2 of FIG. 1 showing the wedging attachment.

FIG. 3 is an exploded view in perspective of a portion of the hot top structure.

FIG. 4 is a view of an alternate form of wedging member.

DESCRIPTION OF THE INVENTION

Although the disclosure hereof is detailed and exact to enable those skilled in the art to practice the invention, the physical embodiments herein disclosed merely exemplify the invention which may be embodied in other specific structure.

The hot top structure of this invention generally includes a number of sideboards or panels 10 suspended in the top of an ingot mold 14 by means of angle irons 12 embedded in the panels 10. The panels 10 generally include an inner face 13, an outer face 15 and edges 16 and are positioned around the entire upper periphery of the inside of the top of the ingot mold 14. The edges 16 of each of the panels 10 are positioned in a parallel spaced relation to the edges of the adjacent panels 10. The panels 10 are therefore free to move relative to each other and away from the inner surface 18 of the ingot mold.

The panels or sideboards 10 are molded from a refractory material such as sand and are bonded together by any of a number of well known adhesives such as sodium silicate or any of the known resins. If the panels are to be used in an ingot mold for casting steel, an exothermic material is usually incorporated in the panel either as a coating or as a part of the panel. As used herein, an insulating panel refers to a panel either including or not including exothermic materials.

In accordance with the invention, means are provided for wedging the panels 10 against the inner surface 18 of the ingot mold 14. Such means is in the form of a pair of clips 20 which are attached to the oppositely disposed edges 16 of adjacent panels 10. The clips are identical in cross section except that one is the mirror image of the other.

More particularly, each clip 20 is bent from a flat piece of sheet metal and includes an inner section 24, an edge section 26 and an outer section 28. The angles between the inner section 24 and edge section 26 and between the edge section 26 and outer section 28 conform to the angles between the inner surface 13 and edge 16 and edge 16 and outer surface 15. As seen in FIG. 2, the angle between the inner section 24 and edge section 26 is an obtuse angle and the angle between the edge portion 26 and outer face portion 28 is acute.

Means are provided on the face 24 to form a downwardly and outwardly inclined channel or groove 30 on each of the clips 20. Such means includes an end section of flange 32 bent inwardly from the inner section 24 at an acute angle and inclined downwardly and outwardly on the inner surface 13 of the panel 10. The end sections 32 on oppositely disposed clips should lie in substantially the same plane.

The panels are wedged against the ingot mold by means of a wedge member 34 which is pushed downwardly into the channels 30 in oppositely disposed clips 20. The wedge member 34 is formed from a rigid plate or panel of either metal or wood and has side edges 36 which converge at approximately the same angle as the channels 30 in adjacent clips. The wedge member 34 is supported on the end section 32 and is firmly seated in the channels 30 with the side edges 36 providing an outward bearing force on said panels. The wedge member can be tapped with a hammer or mallet to firmly seat the panels against the ingot mold. The inner section 24 overlies a portion of the inner surface 13 and acts as a bearing surface to minimize the bearing forces acting on the panel when the wedge member is driven home.

An alternate form of wedge member is shown in FIG. 4 and comprises a V-shaped flexible rod 38 having outwardly diverging legs 40 which converge at their lower

ends 42. The legs 40 of the wedging member are spaced apart a distance greater than the distance between the channels 30 in oppositely disposed clips. The V-shaped rod 38 is inserted into the channels 30 in oppositely disposed clips and is pushed downward to squeeze the legs 40 slightly. The inherent bias of the rod will produce an outward bias force on the inner surface of the panels.

Means are provided for maintaining the location of the clips 20 in adjacent edges of the panels 10 during assembly. Such means comprises a recess 44 in the outer surface 15 of each of the panels 10 and a recess 46 in the side edges 16 of each of the panels 10. The clips 20 are placed on the panels with the outer section 28 seated in the recess 44 and the edge section 26 seated in the recess 46.

Various of the features of this invention are set forth in the following claims

What is claimed is:

1. A hot top structure for an ingot mold, said structure comprising

a number of insulating panels adapted to be suspended around the inside of the top of the ingot mold and having an inner surface and an outer surface,

each panel having edges adapted to be disposed in a spaced relation to the edges of adjacent panels in the hot top structure, a recess in each edge of each of said panels, said recesses in adjacent edges being located opposite each other,

a clip mounted on each edge of said panels and including an edge section adapted to be seated in said recess in the edge of said panel, an inner section overlying a portion of the inner surface of said panel and an end section forming a downwardly and outwardly inclined channel with said inner section, and a wedge member adapted to be positioned in said channel in adjacent clips for wedging said panels against the ingot mold.

2. The hot top structure according to claim 1 wherein said wedge member comprises a flexible V-shaped rod having diverging legs which are compressed between said channels in adjacent clips.

3. The hot top according to claim 1 wherein each of 45 said panels includes a recess in the outer surface.

and said clips each include an outer section adapted to be seated in said recess.

4. A hot top structure in combination with an ingot mold, said structure comprising

a plurality of performed insulating panels positioned around the inside surface of the top of the ingot mold,

each of said panels having edges disposed oppositely to the edges of the adjacent panels and a recess in each edge,

a clip having an edge section seated in said recess in each edge of each panel and having a flange inclined downwardly and outwardly along the inner surface of said panel, and

a wedge member positioned between adjacent clips and supported on said flanges to wedge said panels against the ingot mold.

5. The combination of claim 4 wherein said wedge member includes downwardly converging side edges 20 which correspond to and bear on said flanges.

6. The combination of claim 4 wherein said wedge member includes downwardly diverging legs which are compressed between said flanges.

7. A hot top for an ingot mold, said hot top comprising

a plurality of preformed insulating panels, means for suspending said panels in edge adjacent relation around the inside surface of the ingot mold,

a clip positioned on each edge of each panel with an inner section overlying a portion of the inner surface of the panel and having a downwardly and outwardly inclined flange,

a recess in each edge of said panels for seating each clip on each panel in adjacent relation to the clips on the adjacent panels,

and a wedging member supported on said flanges on adjacent clips to provide an outward bearing force on the adjacent panels.

8. The hot top according to claim 7 wherein said wedging member includes converging side edges to provide the outward bias.

9. The hot top according to claim 8 wherein said wedging member includes outwardly diverging legs to provide the outward bias.
